UNITED STATES PATENT OFFICE.

JOHN J. LANDERS, OF BROOKLYN, NEW YORK.

HOUSEHOLD COAL BOX.

Application filed March 15, 1924. Serial No. 699,480.

To all whom it may concern:

Be it known that I, JOHN J. LANDERS, a citizen of the United States, residing at Brooklyn, in the county of Kings and State 5 of New York, have invented new and useful Improvements in Household Coal Boxes, of which the following is a specification.

The object of this invention is the provision of a means whereby a determined 10 quantity of coal may be effectively stored in a kitchen or other room in a dwelling having a heating plant therein so that access thereto may be conveniently had without necessitating continuous visits to the coal pile.

15 With the above broadly stated object in view and others which will appear as the nature of the invention is better understood, reference is to be had to the drawings which accompany and which form part of this application.

In the drawings:—

Figure 1 is a perspective view of the improvement.

Figure 2 is an approximately central vertical transverse sectional view therethrough.

Figure 3 is a top plan view with the cover of the receptacle removed.

Figure 4 is a sectional view on the line 4—4 of Figure 2.

30 Figure 5 is a sectional view approximately on the line 5—5 of Figure 2.

Figure 6 is a perspective view of the coal conveying member or bucket.

Figure 7 is a sectional view through the 35 bucket or hod showing the slideable front in open position.

My improvement comprises a substantially rectangular receptacle 1 which may be of wood or any other desired material. The 40 receptacle also may be mounted on casters. The receptacle at its front and adjacent to its bottom has a central opening 2 therethrough. On its outer face and in a line with the lower wall provided by the opening 45 there is secured to the face of the receptacle and upwardly inclined plate 3, side elements 4 connecting the plate to the face of the receptacle. On the front face directly above the opening 2 there is secured in the 50 receptacle a downwardly inclined plate 5 that terminates a suitable distance from the rear wall of the receptacle. The plate is designed to direct the coal into the bottom of the receptacle so that access may be had thereto through the opening 2.

Above the directing plate 5 there are se-

cured to the inner sides of the receptacle transverse cleats 6. These cleats are designed to serve as a rest for a coal receiving member or bucket which is broadly indicated by the numeral 7. The bucket, like the receptacle, may be constructed of any desired material and is of a rectangular formation to be snugly received in the receptacle through the open top thereof. The 60 member 7 has its outer face open and has its sides inward of its said open face grooved, as at 8. A suitable brace member 9 is secured between the sides outward of the 65 grooves 8 to strengthen this portion of the 70 structure. The bottom 10 of the bucket terminates in a line with the inner walls of the grooves 8, and the grooves terminate above the lower edges of the sides. The 75 wall 10 from its back to its front is inclined downwardly.

Received in the grooves 8 and closing the outer open face of the bucket or hod there is a slide. The slide includes a lower section 11 and an upper section 12 which is 80 hinged to the inner face of the said section 11, as at 13. The section 11 is of a materially greater length than the section 12. The section 12 has on its outer edge a handle 14, and pivotally or loosely secured 85 to the sides of the bucket there is a bail 15. The bail serves as a means whereby the bucket may be conveniently carried to and from the coal pile or bin as well as permitting the bucket to be easily received in or 90 removed from the receptacle. When the bucket is filled and arranged in the receptacle the slideable front thereof is raised to bring the joint between the sections in a line with the top of the bucket and thereafter the section 12 is swung over the top of the said bucket. This allows the coal from the bucket to gravitate therefrom over the inclined bottom of the said bucket against the directing plate 5 and from thence 95 into the bottom of the receptacle. The coal may be removed through the opening 2 as required. The upwardly inclined plate 3 provides a lip that will prevent coal falling from the receptacle on to the floor in which 100 the device is arranged. A hinged cover 16 105 normally closes the receptacle.

Having described the invention, I claim:—

1. In a device for the purpose set forth, a receptacle having an opening adjacent to the bottom wall thereof, an upwardly inclined lip outward of the opening, cleats in

the receptacle above the opening, a bucket member for holding coal removably arranged in the receptacle and normally resting on the cleats and a slidable front on the bucket member whereby coal may pass therefrom on to the bottom of the receptacle.

2. A household coal box comprising a receptacle having an opening in a line with the bottom thereof, an upwardly inclined lip 10 outward of the opening, a downwardly inclined directing plate in the receptacle and above the opening, cleats above the plate, a removable coal receiving bucket in the receptacle and resting on the cleats, said bucket 15 having an open front, a slidable plate guided in the receptacle for closing the front, said plate comprising hinged sections, whereby when the plate is partly raised the upper section may be swung over the top 20 of the bucket to permit coal gravitating therefrom on to the inclined plate and to be directed therefrom into the bottom of the receptacle.

3. A household coal box comprising a substantially rectangular receptacle having an

elevated bottom, its front provided with an opening terminating in a line with the bottom, an upwardly inclined lip on the outer face of the receptacle in a line with the bottom, a downwardly inclined directing plate 30 in the receptacle above the opening, cleats in the receptacle above the plate, a substantially rectangular coal carrier comprising a bucket designed to be removably received in the receptacle and to rest on the cleats, said bucket having a downwardly inclined bottom, an open face and its sides grooved inward of said open face, a plate comprising hinged sections received in the 35 grooves for closing the open face, a handle on the upper section of the plate, and said upper section designed to be swung over the open top of the bucket to permit coal gravitating therefrom on to the inclined plate in the receptacle to direct said coal on to the bottom of the receptacle, a bail for the bucket, and a hinged closure 40 for the top of the receptacle.

In testimony whereof I affix my signature.
JOHN J. LANDERS.
